J. H. Eberle
ATTORNEY

UNITED STATES PATENT OFFICE.

CHARLES FREDERICK LORENZ, OF EAST ORANGE, NEW JERSEY, ASSIGNOR TO WESTINGHOUSE LAMP COMPANY, A CORPORATION OF PENNSYLVANIA.

MANUFACTURE OF INCANDESCENT LAMPS.

Application filed June 23, 1922. Serial No. 570,484.

My invention relates to a method of bringing the "useful" life and "burn-out" life of electric incandescent lamps into close relation and relates particularly to filaments for such lamps.

An object of the invention is to provide a filament of such character that its life will be automatically terminated when it reaches a point at which an operation of the lamp is uneconomical.

Another object of the invention is to provide a lamp in which the mean lumens per watt during the life of the lamp are substantially constant.

Other objects of my invention will be apparent from a reading of the following specification.

It is customary in the art of incandescent lamp manufacture, when speaking of the life of a lamp, to distinguish between its "useful" life and its "burn-out" life. Inasmuch as these terms are peculiar to the incandescent lamp parlance, and will be frequently used in this application, it may be well to define them. The burn-out life refers to the number of hours of burning of the lamp until a failure of the filament occurs by breakage or otherwise. The useful life of a lamp indicates the number of hours during which it is economical to burn the lamp. Inasmuch as an incandescent lamp decreases in efficiency as it burns, it is obvious that when a lamp has fallen in efficiency beyond a certain point it is more economical to replace it with a new lamp than it is to continue burning the lamp at lower efficiency. This economical limit of operation marks the end of the useful life of the lamp.

In practice, however, most incandescent lamps are used throughout the burn-out life due to a mistaken idea of economy on the part of many users, partly by reason of their inability to determine the economical limit in the life of the lamp.

There is a comparatively wide margin between the useful and the burn-out life of the lamp which in some types of lamps amounts to 100% of "useful" life. This margin represents waste, and, therefore, should be avoided.

By reason of the peculiar form of filament employed in my invention, this waste margin may be eliminated and the present standard for the useful life of a lamp is main-

tained and it has been found in practice that the mean lumens per watt throughout the useful life have been slightly increased. In other words, by reason of my improved filament, a lamp is produced which tends to bring the burn-out life and the useful life into coincidence, while at the same time a lamp is provided which has a useful life equal or slightly better than that of the present standard.

It is well known that one of the elements upon which the life of a lamp depends is the time taken by the filament to disintegrate by vaporization. It is also known that the life of filaments varies depending upon the ratio of the surface area to the volume. Thus a relatively small diameter filament as found in a lamp, for example of 30 watts, 110 volts, will have a useful life of a given number of hours and will continue to burn for an additional amount of time with a gradual decrease in efficiency. The filament of a 30 watt lamp will, however, burn out very near the end of its useful life, whereas, the filament of a 60 watt lamp will continue to burn for a considerable period after its useful life has ended. The reason for this difference in the burn-out life of the two lamps resides in the fact that the surface area of the smaller filament as compared to its volume is great enough to cause a burn-out due to vaporization in an interval of time that is very nearly equal the useful life of the filament.

It will be understood that the filament of a 60 watt 110 volt lamp is essentially of a greater diameter than that of a 30 watt lamp. Therefore since the area of a circle equals πr^2 and the circumference is always equal to πd it follows that the surface area per unit of length of a larger diameter filament will be relatively small whereas the small diameter filament will have a comparatively large surface and small volume per unit of length. In the 30 watt lamp this condition more nearly approaches the ideal in which the useful life of the lamp terminates at about the same time that the filament gives out.

Therefore, for the purpose of benefiting by the advantage gained by the relatively large surface of a small diameter filament I employ, as a light source, a plurality of small filaments preferably entwined or twisted to-

- gether. A filament may thus be provided for use in a lamp of a comparatively high wattage capable of giving the standard amount of useful life but having its useful 5 life and burn-out life close together, and a lamp may be produced having the advantage of the useful and burn-out life of substantially equal lengths as obtained in a lamp of relatively low wattage.
- 10 As an example, it will be understood that a 60 watt, 115 volt lamp will not burn out until its candle power has dropped to an objectionably great extent; that is, the burn-out life of the lamp will be considerably 15 greater than its useful life.
- When practicing my invention to produce a lamp of approximately 60 watts, 110 volts, I employ two filaments of about the diameter used in a 30 watt, 110 volt lamp. It 20 has been found preferable to twist these filaments together and thereby produce a continuous member similar to a cord or rope which may be draped over the supports of a lamp stem in a manner similar to that 25 employed for the mounting of the ordinary single wire filament. Owing to the fact that portions of the twisted wire make contact with each other, it may be desirable to slightly increase the diameter of the twisted 30 wires to compensate for radiation lost by the contacting portions in order to maintain the illuminating value.
- It will be evident that lamps of other wattage may be produced with the same desirable 35 result, for instance, in a 100 watt lamp, three filaments may be twisted together, each of the said filaments being of a diameter as used in a $33\frac{1}{3}$ watt lamp. Thus a relatively large surface area per unit of length or volume of filament will be produced as compared 40 with the surface per unit of length of volume of a single round filament of the same current rating. The total filament surface in the present invention and as heretofore employed are obviously the same.
- The invention will be more fully understood by reference to the accompanying drawing in which Fig. 1 shows a zig-zag type of filament composed of a strand of heavy wire 45 and a strand of relatively fine wire associated therewith; Fig. 2 is an enlarged view of a portion of the filament shown in Fig. 1; Fig. 3 is a view showing a section taken on line III—III in Fig. 2; Fig. 4 is a view 50 of a portion of a modified form of filament showing the strands thereof separated by spacer members to hold the strands apart and Fig. 5 is a view showing a section taken on line V—V in Fig. 4.
- 60 A preferred embodiment of the invention as shown in drawing may include a filament 10 of relatively small cross sectional area entwined or otherwise associated with a filament 11 of a relatively large cross sectional area to produce a filamentary body or

light source 13. A lamp of any given wattage may thus be produced and the burn-out life of such a lamp may be governed by the burn-out life of one of the filaments.

If, for instance, a lamp of 80 watts is desirable, a 50 watt filament may be associated with a 30 watt filament either by twisting the filaments together or the filaments may be spaced apart but connected at intervals throughout their lengths by suitable conductors 14 (see Fig. 4). When the smaller filament reaches its burn-out life and breaks, the portion of the larger filament between the connectors at each side of the break will become over-loaded and in a short time will 75 also break terminating the life of the lamp.

A filament of relatively small diameter when employed for the purpose as above described, may, although acting as a parasite, serve as a controlling member of the filamentary body. It will therefore be understood that by the addition of a filament in which the burn-out life and the useful life are more near the ideal condition, a lamp of 80 any given wattage may be regulated to have 85 its life terminated with that of the parasitic or auxiliary filament.

It will be evident that an auxiliary filament of any configuration in cross section may be employed. It has been found that 90 filaments of different outline in transverse cross section have different life characteristics and a filament of a certain configuration may be produced which will burn out in a given length of time. For example, a 95 flat filament may be employed as the controlling or relatively small filament in conjunction with a relatively large filament, as, for example, that indicated by the numeral 11, to serve as the controlling element to 100 terminate the life of the larger filament. Such flat filament may be twisted or wound about another filament of larger transverse cross sectional area.

Inasmuch as a filament produced in accordance with my invention has the required light source area with a relatively small increase in the weight per unit of length of filamentary material and, furthermore, as the filament for a lamp of given wattage 110 and voltage will necessarily be shorter than commonly employed, it will be appreciated 115 that a saving of said material results.

It will be evident that a stranded filament giving the desired luminosity is an advantage inasmuch as the increased flexibility reduces breakage of the filament during handling in manufacture or subsequent transportation.

My invention therefore not only contemplates the use of a light source comprising a plurality of filaments of such relative proportions that when in operation within the lamp they serve to bring the useful life of 125 the lamp more nearly coincident with the 130

burn-out life, but also provides a more rugged lamp thus increasing its value to both the user and the producer.

While I have described several preferred embodiments of my invention it is obvious that various modifications may be resorted to without departing from the spirit and scope of the appended claims.

What is claimed is:—

- 10 1. The method of approaching an equalization between the useful life and the burn-out life of an electric incandescent lamp which consists in proportioning the ratio between the volume and the surface area of the 15 light source by entwining a plurality of filaments to constitute a filamentary body and in selecting filaments of such size and number as to produce disintegration and failure of the several filaments at the termination 20 of their useful life.
2. The method of controlling the burn-out life of an incandescent electric lamp which consists in associating a filament of relatively large diameter with a filament of 25 relatively small diameter to cause an over-

loading of a portion of one of the filaments upon a failure of another.

3. A filament for an incandescent electric lamp comprising a plurality of strands of different cross-sectional areas twisted together to constitute an integral filamentary body.

4. A filament for an incandescent electric lamp comprising a plurality of strands of different cross-sectional areas. 35

5. A composite filamentary body composed of a plurality of strands, one being of relatively small transverse cross sectional area whereby the failure of said small strand will accelerate the failure of the remainder. 40

6. A filament for an incandescent electric lamp comprising a plurality of entwined strands having different life characteristics to effect a failure of one filament upon the failure of another. 45

In testimony whereof, I have hereunto subscribed my name this 22nd day of June, 1922.

CHARLES FREDERICK LORENZ.
